UNITED STATES PATENT OFFICE.

THOMAS E. MURRAY, OF NEW YORK, N. Y.

PROTECTIVE DEVICE FOR SHEATHED CONDUCTORS.

1,103,983.

Specification of Letters Patent. Patented July 21, 1914.

Application filed April 15, 1912. Serial No. 690,973.

To all whom it may concern:

Be it known that I, THOMAS E. MURRAY, a citizen of the United States, residing at New York, in the county of New York and State of New York, have invented a certain new and useful Improvement in Protective Devices for Sheathed Conductors, of which the following is a specification.

The object of the invention is to prevent conduction of stray currents by the metal sheathing of electrical conductors, and thus to prevent the injurious electrolytic and other effects of said currents upon adjacent objects. To this end, I remove a portion 10 of the sheathing over a given length of the continuous conductor, thus forming a gap over which the current cannot pass. In a long conductor, as many of these gaps may be made as is necessary to the end in view. 15 The gap is covered with a protective sleeve of insulating material, secured to the conductor and suitably packed, as hereinafter explained.

In the accompanying drawings—Figure 1 is a longitudinal section of my device. Fig. 2 is a cross section on the line 2, 2 of Fig. 1. Fig. 3 is a longitudinal section of a modified form of my device, and Fig. 4 is a cross section on the line 4, 4 of Fig. 3.

Similar letters of reference indicate like parts.

A represents a line conductor, having the usual wire B, insulating envelop C and lead sheathing D. In order to prevent conduction of stray currents by the sheathing D, I remove a portion thereof, as shown at E.

F is a sleeve of preferably porcelain or other refractory insulating material, shown as a complete tube in Figs. 3 and 4, and as 40 formed in two half sections G, H, in Figs. 1 and 2, and provided with enlarged spaces at its ends to receive packing I. The middle portion of the sleeve, which directly incloses the denuded portion E of the conductor A, 45 receives a filling J of insulating material, introduced in fluid state, through openings in the sleeve, which are closed by tapered plugs K: said filling afterward hardening in place. The half sections G, H are secured 50 together by the half bands L, M, having meeting flanges to receive headed screws N. The openings in the sleeve for admitting the insulating filling J extend through the upper half band L, and are also closed by the 55 tapered plugs K. In assembling the device, the half sections G, H are placed upon

the conductor and secured by the half bands L, M. The plugs K being removed, the insulating filling J is introduced, and the plugs replaced. The packing I is then put in 60 place: or, if desired, the packing may be inserted before the filling is put in.

The form of my device shown in Figs. 1 and 2 is suited to conditions where it is not desirable to break the continuity of the 65 wire B, or where the ends of the line conductor cannot be reached. In the form shown in Figs. 3 and 4, in which the sleeve F is a complete tube, the half bands are, of course, omitted, and the sleeve after being 70 passed over an end of the conductor, is slid along into proper position, after which the filling J is introduced, as before.

While I may use any suitable packing I at the ends of the sleeve, I prefer to form 75 upon the lead sheath annular flanges, by inserting in the enlargements at the sheath ends, a body of lead floss and consolidating the same, and also causing the same to cohere and become integral with said lead 80 sheath, as fully set out in my application for Letters Patent, Serial No. 661,327, filed November 20, 1911. After these flanges are made, they not only form moisture-proof joints between sheathing and sleeve, but also 85 prevent any sliding of the sleeve on the conductor. Sliding is also measurably prevented by the filling J adhering to the insulating envelop C.

While I have here described the lead 90 sheathing only as removed over the length at E, thus exposing the insulating covering C, it is obvious that, if desired, said covering C also may be removed, the naked wire B then being embedded in the filling J. 95

I claim:

1. In combination, a line conductor covered with an insulation, a metal sheath covering said insulation, a portion of said metal sheath being removed, and a sleeve of insulating material inclosing said insulation where the sheath has been removed and extending inward to said insulation. 100

2. In combination with a metal sheathed continuous line conductor whereof a certain 105 length is denuded of its sheath, a sleeve of refractory insulating material inclosing said denuded portion and said conductor for a distance on each side thereof, a filling of insulating material between said denuded 110 portion of said conductor and said sleeve, the said sleeve having an opening in its wall

for introducing said filling in a fluid state, and means for closing said opening.

3. In combination with a metal sheathed continuous line conductor whereof a certain length is denuded of its sheath, a sleeve of insulating material inclosing said denuded portion and said conductor for a distance on each side thereof, the said sleeve being divided longitudinally into sections, a clamping band for securing said sections together, and a filling of insulating material between

said denuded portion of said conductor and said sleeve; the said sleeve and said band having registering openings for introducing said filling in a fluid state, and means for closing said openings.

In testimony whereof I have affixed my signature in presence of two witnesses.

THOMAS E. MURRAY.
